HYDROCARBON OIL TREATMENT

Lawrence M. Henderson, Narberth, Pa., assignor
to The Atlantic Refining Company, Philadelphia, Pa., a corporation of Pennsylvania

No Drawing. Application October 5, 1932,
Serial No. 636,352

18 Claims. (Cl. 196—13)

The present invention relates to the art of mineral oil refining, and has particular reference to the separation of crude petroleum or petroleum products into fractions of different chemical compositions while of approximately the same distillation range.

In accordance with my invention, crude petroleum or petroleum products, particularly oils of substantial viscosity, are separated into various fractions by means of fractional extraction with furoic compounds, and more particularly with furoic esters: methyl, ethyl, propyl, isopropyl, n-butyl, phenyl, and other furoates being exemplary of the furoic esters contemplated. The "furoic" radical, as the term is employed herein and in the appended claims has the structural formula

The term "furoic acid" as used herein refers to the acid sometimes called pyromuic acid. As well as the esters themselves, mixtures of the esters with one another or mixtures of solvents containing substantial quantities of one or more furoic esters are contemplated within the scope of my invention as selective solvents for the fractional extraction of hydrocarbon oils, particularly, viscous petroleum oils.

It is recognized in the art that mineral oils, such as petroleum, comprise essentially a mixture of hydrocarbons of various groups or homologous series of compounds, such for example, as paraffins of the general formula C_nH_{2n+2} , olefines of the general formula C_nH_{2n} , hydroaromatics and polymethylenes of the same empirical formula, and various other series of compounds of chain and/or ring structures in which the hydrogen to carbon ratio is less than in the foregoing series. A large number of individual compounds of each series and of differing boiling points is present in petroleum.

The various types of crude petroleum, which are generally classified into three groups, namely, paraffinic base, naphthenic or asphaltic base, and mixed base, contain the various series of hydrocarbons mentioned heretofore, in different proportions. For example, in the paraffin base crude oils, such as those obtained from the oil fields of Pennsylvania, there is a relatively high proportion of hydrocarbons having a chain structure and a high hydrogen to carbon ratio, whereas in the naphthenic or asphaltic base crude oils, there is a relatively large proportion of hydro-

carbons having ring structures and a low hydrogen to carbon ratio. Mixed base crude oils, such as are obtained from the mid-continent oil fields, contain hydrocarbons in proportions intermediate these two extremes.

As the use of practically all of the petroleum oils is almost entirely physical, the above described chemical nature of those oils is important in reflecting certain physical characteristics.

The variance in the proportion of the different series of hydrocarbons in paraffinic, naphthenic, and mixed base oils is evidenced by the physical properties of the various oils, and particularly by the relationship of the specific gravity to the viscosity of one oil as compared with another. For example, oils derived from a Pennsylvania crude and having a viscosity of 400 seconds Saybolt Universal at 100° F., will show a specific gravity at 60° F., of about 0.878, whereas an oil of corresponding viscosity produced from a naphthenic crude, such as one from the Gulf Coast area, will show a specific gravity of about 0.933 at 60° F. The relationship between the viscosity and gravity indicates the degree of the paraffinic or naphthenic character of the oil.

If a given crude petroleum be distilled into successive fractions and the specific gravities and viscosities of the several fractions determined, it will be found that they conform to the general relationship:

$$G = a + \frac{1.0752 - a}{10} \log.(V - 38)$$

in which "G" is the specific gravity at 60° F., "V" is Saybolt Universal viscosity at 100° F., and "a" is a constant known as the viscosity-gravity constant. Fractions from each of the different types of crude have different viscosity-gravity constants. Such constants are lower for fractions of the paraffinic crudes than are the constants for fractions of the naphthenic crudes. An article entitled "The Viscosity-Gravity Constant of Petroleum Lubricating Oils" by J. B. Hill and H. B. Coats, which will be found in volume 20, page 641 et seq., Industrial and Engineering Chemistry for June 1928, explains the determination of such constant for several typical oils.

The viscosity-gravity constant is, therefore, an index of the paraffinic or naphthenic character of an oil, since when a given crude is distilled and fractions thereof are collected, regardless of the fraction upon which the specific gravity and the viscosity are taken, when such specific gravity and viscosity are substituted in the formula and the viscosity-gravity constant of the fraction calcu-

lated, the constant will be substantially the same for each of the several fractions of the crude.

The viscosity-gravity constants of the viscous fractions from some of the typical crudes are as follows:

Milltown (Pennsylvania) -----	0.8067
Burbank (mid-continent) -----	0.8367
Guadalupe (Gulf Coast) -----	0.8635
Mirando (Gulf Coast) -----	0.9025

These oils are increasingly paraffinic as the viscosity-gravity constants decrease.

My invention is based upon the discovery that oils containing both the paraffinic series of hydrocarbons and the various naphthenic series may be fractionally extracted with furoic compounds, particularly with furoic esters. The various series of hydrocarbons possess a differential solubility in such solvents. The naphthenic hydrocarbons are much more soluble therein than are the paraffinic hydrocarbons. By means of extraction with furoic esters, for example, with such furoates as propyl furoate or butyl furoate, it is therefore, possible to effect a partial separation of the naphthenic hydrocarbons from the paraffinic and to obtain from an oil containing both classes of hydrocarbons, an oil which is much more paraffinic than the original oil and one which is much more naphthenic. By my invention, for example, it is possible to produce an oil, of the quality normally obtained from Appalachian crudes, from crudes of the mixed base type of the mid-continent area, and conversely, to obtain, from mixed base crudes, oils such as are normally obtained from the naphthenic oils of the Gulf Coast area.

In practicing my invention, I prefer to mix the oil fraction with a suitable proportion of a furoic compound, or mixture of furoic compounds, and more particularly with furoic esters, such as the butyl or propyl esters, at a temperature sufficiently high so that complete solution is effected and a homogeneous liquid obtained. I then cool the mixture to a temperature sufficiently low to cause a separation of the liquid into a two-layer system, the upper layer being a solution of a relatively small amount of the furoic compound or compounds in the more paraffinic portion of the oil and the lower layer comprising a solution of the more naphthenic portion of the oil in the furoic compound or compounds.

Instead of this heating and cooling to effect extraction, I may simply agitate the mixture of liquids at normal temperatures. Where substantial quantities of solid hydrocarbons belonging to the true paraffin series (C_nH_{2n+2}) are present, these solids or waxes remain in the upper layer and may cause it to be solid or semi-solid. Separation of the two layers is then effected, for example, by decantation, and the furoic esters removed from each of the separated oil layers by vacuum distillation or other suitable procedure, thereby obtaining two oils of similar distillation ranges but of otherwise widely different physical characteristics and correspondingly different chemical compositions.

Before removing the furoic ester or esters from the upper and more paraffinic layer of oil obtained in the above described process, I may add a further quantity of furoic ester or esters, or mixture thereof with other solvent where the furoic compound is present to substantial extent, and repeat the process for an extraction of additional naphthenic bodies from the oil. The extraction may be repeated any desired number of

times, thereby producing oils of progressively increasing paraffinicity as evidenced by a decreasing viscosity-gravity constant. In wax-bearing oils, the final undissolved product is a mixture of solid and liquid hydrocarbons. While the exact chemical compositions of these compounds are not known, it is probable that the liquid hydrocarbons are branched chain hydrocarbons of the paraffin series, whereas solid bodies are straight chain paraffin hydrocarbons. This product may be further separated into solid and liquid hydrocarbons by any of the well-known dewaxing processes, such as the cold settling process.

In many instances it will be found of advantage to dewax the oil prior to the extraction process, as this expedites handling the oil during such extraction.

My invention will be further illustrated from the following specific examples:

(1) 100 parts of a previously untreated distillate obtained from a Gulf Coast crude oil and having a viscosity of 612 seconds Saybolt Universal at 100° F., a specific gravity of 0.9303, and a consequent viscosity gravity constant of 0.874 was mixed with 300 parts by volume of isopropyl furoate ($C_4H_9OCOOC_3H_7$), and heated to slightly above the temperature of complete miscibility, which in this particular case was approximately 17° C. The homogeneous liquid which resulted was cooled with agitation to -12° C., and allowed to settle, whereupon a two-layer system formed which consisted of an upper undissolved oil layer comprising 57.2 parts of mixture and a lower layer of oil dissolved in isopropyl furoate comprising approximately 342.8 parts of mixture. After separation, the layers were each freed from isopropyl furoate by vacuum distillation. The isopropyl furoate dissolved fraction yielded 285.6 parts of isopropyl furoate and 57.2 parts of oil having a viscosity of 914 seconds Saybolt Universal at 100° F., a specific gravity of 0.9606, and a viscosity-gravity constant of 0.914. The undissolved fraction yielded 14.4 parts of isopropyl furoate and 42.8 parts of an oil having a viscosity of 358 seconds Saybolt Universal at 100° F., a specific gravity of 0.8933, and a viscosity-gravity constant of 0.833.

(2) 100 parts of residual stock from a paraffin base crude having a viscosity of 103 seconds Saybolt Universal at 210° F., a specific gravity of 0.8905, and a consequent viscosity-gravity constant of 0.808 was mixed with 300 parts by volume of n-butyl furoate and heated to slightly above the temperature of complete miscibility, which in this case was approximately 47° C. The homogeneous liquid which resulted was cooled with agitation to 20° C., and allowed to settle, whereupon a two-layer system formed, which consisted of an upper undissolved oil layer comprising 81.5 parts of mixture and a lower layer dissolved in n-butyl furoate comprising approximately 318.5 parts of mixture. After separation, the layers were each freed from n-butyl furoate by vacuum distillation. The n-butyl furoate dissolved fraction yielded 285.9 parts of n-butyl furoate and 32.6 parts of oil having an increased viscosity and specific gravity. The undissolved fraction yielded 14.1 parts of n-butyl furoate and 67.4 parts of an oil having a viscosity of 102 seconds Saybolt Universal at 210° F., a specific gravity of 0.8805, and a viscosity-gravity constant of 0.796.

From the above examples it will be seen that by extraction with furoic esters, there may be obtained oil fractions which are respectively higher in paraffinicity and naphthenicity than the origi-

nal oil. By repetition of the extraction process upon the furoic ester undissolved fraction, oils may be obtained which are increasingly paraffinic, as evidenced by progressively decreasing viscosity-
5 gravity constants.

It is evident that my process is practically independent of the particular nature or source of the crude oil, and that there may be produced thereby oils of desired characteristics from oils
10 which heretofore have not been used as a source of oils of such desired characteristics.

For example, my process may be employed to produce from petroleum of a mixed base type such as would, on normal batch distillation, give
15 a residuum with a viscosity of 150 seconds Saybolt Universal at 210° F., with a specific gravity of 0.928 or more, a lubricating stock with a viscosity at 210° F. of 150 seconds Saybolt Universal, or more, and a specific gravity not higher than 0.910.
20 This latter combination of properties is typical of cylinder stocks produced from Pennsylvania crudes.

In the extraction at ordinary temperatures of oils with furoic esters, particularly in extraction
25 of the more naphthenic oils, it is found that some of the higher molecular weight furoic esters approach complete miscibility with the oil. A furoic ester of low enough molecular weight must be used to obtain a two layer system with the oil
30 sought to be separated. In general, a naphthenic oil will necessitate a lower molecular weight ester than a paraffinic oil. Alkyl esters of furoic acid or mixtures thereof having an average molecular weight of the order of or lower than that of
35 n-butyl furoate, viz., a molecular weight of 168, have a substantial selective action on hydrocarbon oils in general, excepting, possibly, some very naphthenic oils. A furoic ester or mixture of furoic esters having an average molecular weight
40 of the order of that of ethyl furoate or propyl furoate is, in the case of many hydrocarbon oils, preferred. The very low molecular weight furoic esters, for example, methyl furoate, may be found, in the case of very paraffinic oils, to be too im-
45 miscible to produce a substantial separation between the paraffinic and naphthenic components of the oil.

While furoic esters, including those formed by combination of alkyl and those formed by combination of aryl radicals with the negative furoic radical, are contemplated as selective solvents for oil, yet, due to the fact that the aryl, i. e., aromatic furoates are difficultly obtainable commercially, the furoates formed with alkyl, i. e., aliphatic radicals are, from the point of practical operation, primarily contemplated. However, where aromatic furoates are employed, either alone or in mixture with other aromatic and/or aliphatic furoates, such aromatic furoates
55 must be chosen, depending on the paraffinicity or naphthenicity of the oil to be separated, so that such furoates or mixture of furoates will be neither too immiscible nor uniformly miscible with components of the oil.

While the miscibility of such esters with oils may be increased by increasing the temperature of the mixture and decreased by decreasing its temperature, yet practicability requires that the oil be not treated at too high a temperature, or-
60 dinarily not at temperatures above 150 to 175° C., or of that order, nor at such low temperatures that the viscosity of the oil becomes great, for example, not below temperatures of the order of -15° C. This temperature range of -15° to
65 175° C. is only exemplary of the general range

of temperature which is ordinarily found to be practical, and I do not intend to hereby confine myself to this temperature range. The particu-
70 lar selective solvent and oil and also the presence conditions employed in any selective extraction process are factors which influence the choice of practical temperature conditions.

In extracting oils containing appreciable amounts of wax, such oils may be dewaxed, for example, by cold settling or centrifuging prior to carrying out the extraction. My process is operable, however, in the absence of preliminary dewaxing.

Hereinabove, mixtures of solvents have been referred to. It is to be understood that in such mixtures the constituent solvents will not react with one another, nor with the oil upon which they are to be used, and that such mixtures will contain substantial amounts of furoic esters.

For brevity, in the appended claims, the term furoic esters is employed in a generic sense to include one or a mixture of esters of furoic acid, or a mixture of solvents which contains substantial quantities of such esters.

Also, where herein, or in the appended claims, an oil is specifically referred to as being "viscous", it is to be understood that the oil is of substantial viscosity, i. e., of the order of 50 seconds Saybolt Universal at 100° F., or more.

What I claim is:

1. In the art of refining mineral oils, the process which comprises separating an oil containing paraffinic and naphthenic hydrocarbons into fractions respectively richer in paraffinic and naphthenic compounds by extracting said oil with a furoic ester.

2. In the art of refining mineral oils, the process which comprises fractionally extracting an oil containing paraffinic and naphthenic hydrocarbons with a furoic ester to produce fractions of the oil respectively richer in paraffinic and naphthenic compounds.

3. In the art of refining mineral oils, the process which comprises adding a furoic ester to an oil containing paraffinic and naphthenic hydrocarbons, heating the mixture to such temperature as to effect solution, cooling the solution to form a two layer system, and separating the upper layer from the lower layer.

4. In the art of refining mineral oils, the process which comprises adding a furoic ester to an oil containing paraffinic and naphthenic hydrocarbons, heating the mixture to such temperature as to effect solution, cooling the solution to form a two layer system, removing the lower layer, and similarly retreating the upper layer with a furoic ester.

5. In the art of refining mineral oils, the process which comprises bringing a mineral oil containing paraffinic and naphthenic hydrocarbons into contact with a furoic ester, thereby to effect solution of a portion richer in naphthenic hydrocarbons in the furoic ester, separating the solution so formed from the remainder of the oil, and removing the furoic ester from both portions of the oil, thereby to obtain fractions of the oil respectively richer in paraffinic and naphthenic hydrocarbons.

6. The process for separating mineral oils containing paraffinic and naphthenic hydrocarbons into fractions which comprises bringing the oil into contact with a furoic ester, thereby to effect solution of a portion of the oil richer in naphthenic hydrocarbons in the furoic ester, separating the solution so formed from the remainder.

of the oil, and distilling the furoic ester from both of the portions of the oil, thereby to obtain fractions of the oil respectively richer in paraffinic and naphthenic hydrocarbons.

5. In the art of refining mineral oils, the process which comprises bringing a mineral oil containing paraffinic and naphthenic hydrocarbons into contact with a furoic ester, thereby to effect solution of a portion richer in naphthenic hydrocarbons in the furoic ester, separating the solution so formed from the remainder of the oil, and re-treating the oil remaining with additional amounts of furoic ester.

6. A method of producing paraffinic lubricating oil from mixed base crude which comprises distilling the crude and bringing a portion thereof into contact with a selective solvent containing a substantial proportion of an alkyl ester of furoic acid, thereby partially dissolving the oil, separating the furoic ester solution of oil so treated, and removing the furoic ester from the treated oil.

7. The process of producing a lubricating stock of specific gravity less than 0.910 and of Saybolt Universal viscosity greater than 150 seconds at 210° F. from a crude petroleum which on normal distillation yields a residuum of 150 seconds viscosity at 210° F., and a specific gravity greater than 0.928, which comprises producing a residuum from the crude petroleum, and extracting said residuum from said crude petroleum with a selective solvent containing at least one alkyl ester of furoic acid from the group consisting of propyl and butyl furoates.

8. In the art of refining mineral lubricating oil containing naphthenic and paraffinic hydrocarbons, the step of fractionally extracting the oil with a selective solvent containing at least one alkyl ester of furoic acid from the group consisting of propyl and butyl furoates, to effect a separation of fractions respectively richer in paraffinic and naphthenic compounds.

9. The process of producing a lubricating stock of specific gravity less than 0.910 and of a Saybolt Universal viscosity greater than 150 seconds at 210° F. from a crude petroleum which on normal distillation yields a residuum of 150 seconds Saybolt Universal viscosity at 210° F. and a specific gravity greater than 0.928, which comprises separating a residuum from said crude petroleum and bringing such residuum into contact with a selective solvent containing a substantial amount of an alkyl ester of furoic acid from the group consisting of propyl and butyl furoates, to effect solution of a portion thereof with the solvent, separating the solvent solution of oil from the portion which does not dissolve therein, and removing the solvent from the oil of said solution.

10. In a process for separating a viscous mineral oil containing paraffinic and naphthenic hydrocarbons into fractions which are respectively richer in naphthenic hydrocarbons and paraffinic

hydrocarbons other than wax, the step which comprises extracting the oil with a selective solvent containing a substantial amount of an alkyl ester of furoic acid.

11. In a process for separating viscous mineral oil liquid at ordinary temperature containing paraffinic and naphthenic hydrocarbons into fractions respectively richer in paraffinic and naphthenic hydrocarbons, the step which comprises extracting the oil with an alkyl ester of 10 furoic acid.

12. In a process for separating a substantially wax free viscous mineral oil containing paraffinic and naphthenic hydrocarbons into fractions respectively richer in paraffinic and naphthenic 15 hydrocarbons, the step which comprises extracting the oil with an alkyl ester of furoic acid.

13. The process of treating a viscous fraction of a crude oil of one type containing paraffinic and naphthenic hydrocarbons to procure a fraction having the quality of a corresponding fraction of a crude oil of different type having a greater content of paraffinic hydrocarbons, which comprises extracting the viscous fraction with a selective solvent containing an alkyl ester of furoic 20 acid.

14. The process of treating a viscous fraction of a mixed base crude oil to procure a fraction having the quality of a corresponding fraction of a paraffinic base crude, which comprises extracting the viscous fraction with a selective solvent containing an alkyl ester of furoic acid, and separating the oil so treated into portions respectively 30 richer in paraffinic and naphthenic compounds.

15. In the art of refining mineral oils, the process which comprises adding to a viscous oil liquid at ordinary temperatures, containing paraffinic and naphthenic hydrocarbons, a selective solvent containing an alkyl ester of furoic acid, heating the mixture to a temperature sufficient to effect 40 solution, cooling the solution to a temperature sufficient to form two layers respectively richer in naphthenic hydrocarbons and paraffinic hydrocarbons other than wax, and separating the upper layer richer in paraffinic hydrocarbons from the 45 lower layer richer in naphthenic hydrocarbons.

16. In the art of refining mineral oils, the process which comprises adding to a viscous oil liquid at ordinary temperatures, containing paraffinic and naphthenic hydrocarbons, a selective solvent 50 containing an alkyl ester of furoic acid, heating the mixture to a temperature sufficient to effect solution, cooling the solution to a temperature sufficient to form two layers, separating the solvent and paraffin wax from the upper layer, and separating the solvent from the lower layer to produce one fraction richer in paraffinic and a second fraction richer in naphthenic hydrocarbons than said viscous oil.
